ATOMIZING OIL BURNER AND IGNITION
MEANS THEREFOR

George D. Smith, Brooklyn, N. Y.

Application September 8, 1947, Serial No. 772,761

1 Claim. (Cl. 158—28)

1

This invention relates generally to ignition means and more particularly to an ignitor for fuel in a dispersed state.

It is among the objects of the present invention to provide structure for the ignition of fuel flares or fuel flames, particularly those required to burn in the atmosphere, such as fog dispersal burners which must function in rain, wind and adverse weather conditions.

In connection with the dispersion of fog from such areas as airfields, it is necessary that fuel burners used for this purpose be quickly ignitable. This is so for several reasons. First, with large areas over which the fog dispersal burners are distributed, it is desirable that they be ignited at the exact time when their use is necessary. This may be readily understood, since if the burners do not light at the desired time, the fog dispersal is interfered with, which may cause bad landings of the aeroplanes. Another reason for prompt action is that with a large number of burners, fuel consumption is relatively high and if it were necessary to light the burners in advance of their actual use, there would be considerable waste of fuel.

Prompt lighting of the burners is also necessary because it is most likely that it will be necessary to ignite them when the weather conditions are adverse accompanied by wind and rain.

It is another object of the present invention to provide a fuel flare or flame ignitor which, when energized will substantially remain within a predetermined range of temperatures so that the ignition temperature may be obtained to properly ignite the particular fuel being used.

Another object herein lies in the provision of structure of the class described which is simple, so as to be low in initial cost since a relatively large number of ignitors are required for a single airfield.

Another object herein lies in the provision of ignitor structure which is substantially weather-proof so that the same may have long continued trouble-free operation requiring a minimum of servicing.

Another object herein lies in the provision of a fuel flare ignitor which is electrically operated so that the same may be remotely controlled with a maximum of speed and convenience.

A feature of the invention lies in the fact that the power requirement of the ignitor is relatively low. This permits a large number of ignitors to be operated off a single service line of relatively low power transmitting capacity.

2

Another object of the present invention lies in the provision of an ignitor which maintains a substantially constant predetermined temperature by virtue of the structure incorporated there-in which protects the heater element from ambient external influences. In accordance with the present invention, a heater element is used which may be energized and controlled from a remote point and in which the heater element is disposed within a body element having a downwardly opening recess, said heater element being thus protected from mechanical injury and weather conditions so that with a relatively low power input adequate constant temperature for ignition purposes is maintained.

The present invention has among its features the overcoming of the disadvantages associated with prior art ignitors in which because of the lack of protection for the heater element, ambient external influences such as wind, fog or rain of variable intensity would lead to the disintegration of the heater element. Thus, for example, where the wind velocity was sufficient to carry away for example, 100 watts of energy, it was necessary to supply sufficient additional energy to bring the heater element to the desired predetermined temperature. If the wind velocity decreased, the reduction in cooling would cause the heater element to burn out. On the other hand, if the wind velocity increased, the temperature of the heater element would drop so that it was no longer effective to produce proper ignition.

Another object herein lies in the provision of fuel burner and ignitor combination structure wherein the ignitor is stationary with respect to the burner and wherein fuel is projected by the burner toward the ignitor at the commencement of combustion, the projection of the fuel or its position receding with respect to the ignitor after combustion has occurred for a short period of time. Thus, no moving parts or any other means are required to shift the position of the ignitor and yet, very quickly after ignition of the fuel takes place, the ignitor is in effect removed from the flame.

These objects and other incidental ends and advantages will more fully appear in the progress of this disclosure and be pointed out in the appended claim.

50 In the drawings in which similar reference characters designate corresponding parts throughout the several views:

Fig. 1 is a fragmentary elevational view, partly in vertical section, showing an embodiment of 55 the invention.

Fig. 2 is a plan view of the base element of the ignitor with the cover element removed.

Fig. 3 is a fragmentary vertical sectional view as seen from the plane 3-3 on Fig. 1.

Fig. 4 is a schematic diagram.

The ignitor, generally indicated by reference character 10, includes broadly a body element 11, a heating element 12, a support element 13, and energy supplying means 14.

The ignitor 10 is used in combination with a burner 15 and is fixed at a predetermined position with respect thereto. As seen in Fig. 1, the support element 13 is joined to the lower portion 16 of the burner element 15 by a connector element 17. While I have shown in Fig. 1, the ignitor 10 as being fixed in position with respect to the burner 15 by the connector element 17, other suitable means for this purpose may be employed.

The burner 15 is of a type known in the art to which the present invention relates in which the flow of fuel may be controlled and the shape of the dispersed fuel cone above the burner may be controlled. While I have shown only one burner 15 and one ignitor 10, as will be obvious, any desired number of these units, indicated generally by reference character 25, may be arranged in suitable fashion to accommodate the area being cleared of fog. The burner 15, when operating under low pressure, controlled for example by the input valve 28 and the output valve 29, may have an initial broad based inverted cone of dispersed fuel disposed above it. The relatively outer margins of such a cone are indicated by the dot dash lines on Fig. 1 (reference character 40). When the pressure of the fuel in the burner 15 builds up to equilibrium value, the cone of dispersed fuel narrows so that the same may be indicated, for example by the dash double dot lines on Fig. 1 (reference character 50). Thus, immediately following the manipulation of the valves 28 and 29 to set the fuel supply for a smaller or larger quantity, the initial cone of dispersed fuel for a particular setting of fuel supply will contact the ignitor 10 and after pressure has reached a state of equilibrium, the cone will automatically narrow so that the ignitor 10 is no longer located within the area of most intense heat.

Turning to the ignitor 10, the body element 11 and the support element 13 are preferably composed of suitable heat resisting material. This, for example, may be of molded electrical insulating and heat resisting material. Molded asbestos of this character may be used for this purpose. The body element 11 includes a base member 20, and a cover member 21. The base member 20 includes a bottom surface 22, a top surface 23, a rear surface 24, a front surface 26 and side surfaces 27 and 30. Rearwardly of the front wall 26, the base member 20 is provided with an opening 33 of elongated character extending lengthwise between the side surfaces 27 and 30. The opening 33 has a front wall 34, a rear wall 35 and side walls 36 and 37. The base member 20 is provided with a plurality of orifices to receive contact and assembly screws 41-42 and 43-44 respectively, as will more fully appear. The opening 33 is arranged at a forwardly and downwardly diverging angle so that the front wall 34 and the rear wall 35 are downwardly and outwardly angularly disposed. The walls 34 and 35 are preferably parallel. The front wall 26 is also angularly disposed and preferably parallel to the wall 34.

The cover member 21 has a bottom surface 45, a top surface 46, a rear surface 47, a forward

surface 48. The front surface 48 is preferably co-planar with the surface 26. The side surfaces 51 and 52 are preferably co-planar with the side surfaces 27 and 30.

There is a front recess 55 and a rear depression 56. The depression 56 is of sufficient depth and size to accommodate the upper ends of the contact screws 41 and 42 together with the conductors 60 and 61 as well as the terminals of the heating element 12 and the washers and nuts thereon.

The front recess 55 includes a top surface 62, side surfaces 63 and 64, a rear surface 65 and a front surface 66. The front surface 66 is co-planar with the front surface 26. The rear wall 65 forms a web separating the front recess 55 from the rear depression 56, and is provided with a pair of spaced indentations where the terminals of the heater element 12 may pass rearwardly to become secured upon the contact screws 43 and 44. The lower portions of the screws 41 and 42 are countersunk at their heads in the lower wall surface 22, while the lower of the two nuts on each of said screws is countersunk in the top surface 23. The heater element is preferably in the form of a coil of resistance wire, and is desirably stiff enough to support itself even when at high temperature.

A mounting block 19 is suitably secured in the upper open end of the support element 13, the latter preferably being in the form of tubing which is rectangular in cross section. Block 19 has a pair of orifices through which the screws 43 and 44 upwardly project and the lower of the two nuts on each of said screws is countersunk in the upper surface 23. These last mentioned nuts hold the base member 20 on top of the support 13. The cover member 21 also has a pair of holes through which the upper ends of the screws 43 and 44 project, and the top nuts hold the cover member in place.

Operation

When the unit 25 is set for operation, it will be seen that the heater element is disposed within a cavity, the opening of which faces generally toward the opening of the burner through which the fuel emerges, said cavity, however being laterally offset with respect to the axis of the principal direction of fuel movement as it leaves the burner.

When it is desired to ignite the burner 15, the switch 80 is closed which completes the circuit from a source of electricity (not shown) to the stepdown transformer 81. The secondary winding of the transformer is connected via the conductors 60 and 61 through the contact screws 41 and 42 and associated conductive parts to the heater element 12. The action of ignition and the inception of combustion is relatively rapid and the operation, as presently understood is as follows: The heater element 12 quickly reaches the predetermined temperature which of course is determined from the flash point of the fuel used. Depending upon the particular type of burner used, the valves 28 and 29 or either one of them are set to permit the fuel to emerge from the burner. In the beginning, the fuel at the selected setting, because of inertia or for other reasons (even deliberate control), leaves the burner at a relatively wide angle (see the cone 40 on Fig. 1). Fuel, either in the form of a condensation of droplets or in the form of a spray or a gas or liquid, is deposited within the recess 55 and/or upon the heater element 12.

The heater element quickly ignites this deposited material, which in turn expands and flashes back and is forcibly ejected to ignite the main fuel stream leaving the burner 15. By virtue of the shape of the recess, the burning material must of necessity leave the recess through the opening and therefore move generally in the direction of the fuel stream. Immediately after ignition, the inertia of the fuel is overcome and the velocity of the fuel stream is increased by reason of increase in pressure so that the cone of said stream becomes narrowed (see reference character 50 in Fig. 1). This results in a recession of the fuel stream away from the ignitor and depending upon the pressure and flow of the fuel is accompanied by a movement of the base of the flame away from the burner opening. This, together with the ambient air which is pulled along with the flame results in the envelopment of the ignitor by cooler air with a consequent protection of the ignitor from the areas of intensely high temperature.

The heater element may be relatively small and is preferably one having a low thermal capacity in the order of 30 watts; heater elements of such size having been successfully operated, and have successfully performed with as low as 10 watts. Through the use of low voltage supply to the heater element, since the ignitors are principally used in locations exposed to bad weather conditions, the frequency of electrical trouble, such as short circuit, or leakage is reduced.

It may thus be seen that I have disclosed an ignitor that will effect ignition and remain away from the flames without the need for any movable parts or any other means to remove the ignitor from the flame area, and that the natural movement of the fuel causes an upward current of air which tends to keep the ignitor housing cooler than it would otherwise be.

I wish it to be understood that I do not desire to be limited to the exact details of construction shown and described, for obvious modifications will occur to a person skilled in the art.

I claim:

In an oil burner the combination of a burner element having a nozzle, an ignition device, a support for joining and permanently holding said burner element and said ignition device in fixed off center relation to each other, said ignition device including a standard and a cap therefor, said cap member forming a relatively short un-

restricted recess which has its opening forwardly of and pointed toward the nozzle of said burner element, a hot wire igniting element mounted in said recess near the closed end thereof to protect said igniting element from foreign particles and air currents tending to cool said element, means for supplying fuel under reduced pressure to said nozzle to atomize said fuel and to spray it in a predetermined wide cone area at the start of fuel supply to said nozzle and in a narrower predetermined cone area when the fuel pressure at the nozzle has reached its equilibrium value, said igniting element being within said wide cone area whereby it is in direct unobstructed line with a portion of atomized fuel of said wide cone at the start, whereby said atomized fuel emerging from said nozzle at the start is partly intercepted by said recess of said ignition device and whereby said igniting element receives and ignites some of said atomized fuel in said recess, said recess also constructed to act as a chamber with its axis so directed as to direct ignited atomized fuel into igniting relationship to the remainder of the atomized fuel issuing from said wide cone area of said burner nozzle, said ignited fuel in said recess upon expanding being forcibly ejected from said recess into the main atomized fuel stream to ignite the same, said ignition device being entirely outside the narrower fuel cone area during normal operation.
